UNITED STATES PATENT OFFICE.

DANIEL E. HERTZLER AND CHARLES F. SMITH, OF BURLINGTON, IOWA.

FOOT-MEASURING DEVICE.

SPECIFICATION forming part of Letters Patent No. 745,184, dated November 24, 1903.

Application filed March 5, 1903. Serial No. 146,333. (No model.)

To all whom it may concern:

Be it known that we, DANIEL E. HERTZLER and CHARLES F. SMITH, citizens of the United States, and residents of Burlington, in the county of Des Moines and State of Iowa, have made a certain new and useful Invention in Foot-Measuring Devices; and we declare the following to be a full, clear, and exact description of the same, such as will enable others skilled in the art to which it appertains to make and use the invention, reference being had to the accompanying drawings, and to letters and figures of reference marked thereon, which form a part of this specification.

15 Figure 1 is a perspective view of the invention. Fig. 2 is a side elevation of the same. Fig. 3 is a plan view of the invention. Fig. 4 is a plan view of a modified form of the invention. Fig. 5 is a bottom plan detail view 20 of part D' and slide d', showing connection of spring d². Fig. 6 is a detail view of slide d'. Fig. 7 is a detail perspective view of indicating-slide E. Fig. 8 is a detail cross-section on line 88, Fig. 3.

25 This invention has relation to devices for measuring the foot for boots and shoes, and has for its object the provision of size-indicating devices which will expedite the fitting, providing means for readily ascertaining the 30 correct length and width of the shoe for both right and left foot and in all cases.

With this object in view the invention consists in the novel construction and combinations of parts, all as hereinafter described, and 35 pointed out in the appended claims.

Referring to the accompanying drawings, the letter A designates a platform or base of general rectangular form and made of wood or other suitable material and having a plane 40 upper surface of sufficient length and breadth for the purpose in view. This plate has at the rear an upwardly-projecting heel-rest B, longitudinally adjustable by means of screws b engaging slots b'. At each side of the base 45 A are longitudinal bars C and C', one bar, C, being fixed and extending from one end of the heel-rest to the opposite end portion of the base, while the other bar, C', is arranged to have a lateral movement to accommodate 50 feet of different widths. For this purpose a transverse recess D is formed in the base-plate, into which is inset a transverse metal

piece D', having formed therein a lengthwise slot d. The bar C is fastened to this piece D' at one end thereof, and working in the slot d 55 is a slide d', fastened to the bar C' and acted upon by coil-spring d², fixed to the under side of metal piece D' to force it inwardly upon the base-plate toward bar C, a set-screw d³ being arranged to fix the adjustment of bar C'. 60

Upon the upper surfaces of the bars C and C', at the central portion thereof, is the size-scale x, running from "1" to "14," inclusive, with subdivisions for half-numbers, although such scale may include children's sizes, running from men's "14" or "15," if desired, to children's "9," the number "13" for children being placed next below the number "1" for men and "12," "11," "10," and "9" following the "13," the oblique lines of the width-scale being extended to intersect this children's scale. An indicating-slide E upon each bar has a concave inner surface e to receive the ball of the foot, is open at the top to expose the scale below, and gives the correct 75 length or size of the shoe by shoe-numbers.

At the forward end portion of the bars C C', upon the inner surface thereof, is marked the toe-scale y from "1" to "13," inclusive, with subdivisions for half-numbers, and correctly estimating in connection with indicating-slide F, having set-screws upon each said bar, the length or size of the foot by shoe-numbers, which will ordinarily agree with the size given by the scale x, but in any case in 85 feet of unusual formation will give the proper length of the shoe.

The toe-scale may be likewise modified to include children's sizes, as before stated, for the length-scale. It now remains to find the 90 width of the shoe, and for this purpose we provide a width-scale Z, of diagonal or oblique lines or divisions intersecting the size-scale x upon movable bar C', said oblique lines being marked "9," "8," "7," "EE," "E," "D," 95 "C," "B," "A," "AA," and "AAA." When the adjustment of bar C', which works over scale Z, is fixed, or when said bar rests against the side of the foot, the opposite side being against bar C, the correct width will be indicated by the intersection of the division or subdivision, marking the size in the scale x, with one of the divisions of the width-scale Z.

In Fig. 4 of the drawings is shown a modi-

fied form of our invention, wherein the width-scale is represented by longitudinal lines or divisions 1, parallel to the sides of the base-plate, and which act in connection with triangular plate 2, carried by the movable bar C' and bearing the divisions of the size-scale x to estimate the width of the shoe.

5 In calculating the size or length of the foot by the size and toe scales x and y the bars C 10 and C' and their slides are used separately for the right and left foot—that is to say, but one ball-slide and one toe-slide for each foot.

Having thus described our invention, what we claim as new, and desire to secure by Letters Patent, is—

15 1. In a foot-measuring device, a width-scale upon the base-plate, and means having a movable member operating over such width-scale for indicating the length and width of 20 the foot, substantially as specified.

2. In a foot-measuring device, the heel-rest, the fixed side bar, the spring-pressed movable side bar, means for securing the movable side bar in adjusted position, and means in connection with said side bars for indicating the length and width of the foot, substantially as 25 specified.

3. In a foot-measuring device, the base-plate, the heel-rest, the fixed side bar, and 30 movable side bar bearing the size-scale, the width-scale upon the base-plate, and means acting in connection therewith for indicating the length and width of the foot, substantially as specified.

35 4. In a foot-measuring device, the base-plate, the heel-rest, the fixed side bar and the movable side bar, bearing the size and toe

scales, the width-scale upon the base-plate, and the ball and toe slides carried by said side bars, substantially as specified.

5. In a foot-measuring device, the base-plate, the heel-rest, the fixed side bar and the movable side bar bearing the size and toe scales, the width-scale upon the base-plate intersecting the size-scale, and the ball and 45 toe slides upon said side bars, substantially as specified.

6. In a foot-measuring device, the base-plate, having a transverse recess, the heel-rest, the fixed side bar, the movable side bar, 50 having a slide working in said recess, the coil-spring connected with said slide, said side bars bearing the size and toe scales, the width-scale upon the base-plate, and intersecting the size-scale, and the ball and toe slides 55 upon said side bars, substantially as specified.

7. In a foot-measuring device, the base-plate, having a transverse recess, the heel-rest, the fixed side bar, the movable side bar, 60 having a slide working in said recess, the coil-spring connected with said slide, said side bars bearing the size and toe scales, the width-scale upon the base-plate, and consisting of a series of oblique lines intersecting the size-scale, and the ball and toe slides upon said 65 side bars, substantially as specified.

In testimony whereof we affix our signatures in presence of two witnesses.

DANIEL E. HERTZLER.
CHARLES F. SMITH.
